(57) **CLAIM**

The ornamental design for a control handle for tap as shown and described.

DESCRIPTION

1. Control handle for tap

1.1 is a perspective view of the design 1;

1.2 is a front view thereof;

1.3 is a left view thereof;

1.4 is a right view thereof;

1.5 is a top view thereof;

1.6 is a bottom view thereof.

The broken lines illustrate portions of the control handle for tap that form no part of the claimed design.
